UNITED STATES PATENT OFFICE.

CHARLES C. PARKER, OF BALTIMORE, MARYLAND, ASSIGNOR TO THE HYGIENIC BOTTLE CAP COMPANY, OF BALTIMORE, MARYLAND, A CORPORATION OF MARYLAND.

BOTTLE CAP.

1,414,705.

Specification of Letters Patent. Patented May 2, 1922.

Application filed January 23, 1920. Serial No. 353,566.

To all whom it may concern:

Be it known that I, CHARLES C. PARKER, a citizen of the United States of America, residing in the city of Baltimore, State of Maryland, have invented certain new and useful Improvements in Bottle Caps, of which the following is a specification.

Bottle and jar caps of the type which set inside the lip of the bottle or jar, and are 10 provided with a tab or tongue by means of which they are lifted and withdrawn are very familiar to the public, particularly in their use in connection with bottles and jars for dispensing milk. These caps, in the 15 form in which they are used, embody numerous defects and objectionable features which have caused them to be regarded more in the light of the most available expedient than as an actual solution of the 20 problem presented by the necessity for a cheap and effective closure for jars and bottles, particularly milk bottles.

Chief among these defects are leakage, lack of protection to the milk and the lip 25 of the bottle over which the milk is poured, and almost universal failure of the tab by breakage in the attempt to use it to withdraw the cap; also the tabs are ordinarily so embedded in the aperture from which 30 they are cut that they cannot be raised to a position in which they can be grasped without the use of some instrument, as a knife, which would be almost equally effective in removing the cap without the tab, 35 and the cap may be removed and a portion of the milk withdrawn and some other liquid substituted, or the milk may be otherwise tampered with, and the cap replaced by an unauthorized person without leaving 40 evidence of the fact.

The present invention relates to a cap or jar or bottle closure, in which these defects are eliminated; that is the cap includes and embodies means for protecting the bottle 45 lip from dirt, a closure which is sufficiently tight to prevent leakage, a tab so arranged that it is always conveniently placed for engagement by the fingers, so that no instrument is necessary to raise the tab or 50 remove the cap, and which is so formed that it has sufficient strength to overcome the resistance offered in removing the cap, without tearing; and in addition to these advantages, the cap is so constructed, and when sealed, 55 is so tightly engaged, that it cannot be re-

moved without so defacing it that the fact that the bottle was tampered with since it was filled will be clearly apparent.

In the accompanying drawing, I have 60 illustrated a cap embodying my invention in the preferred form, the same being shown in connection with a fragmentary section of the bottle neck sufficient to illustrate the application of the cap.

In the drawing:

Figure 1 is a vertical central section, showing the cap applied to a bottle.

Figure 2 is a top plan of the cap.

Figure 3 is a plan of the plug or stopper member.

Figure 4 is a bottom plan of the cap.

Figure 5 is a plan of the plug reinforcing and closing member.

Referring to the drawings by numerals:

The bottle or jar neck is shown as having 75 the opening enlarged at the top to form an annular chamber, 2, and a shoulder or seat, 3, also annular or extending around the inner circumference of the bottle opening. The cap, indicated in a general way by 80 reference character, 40, preferably consists of three pieces, an outer lip covering member, 5, a hollow plug member, 4, in the form of a flanged paper disc, and a reinforcing and closing member 8. The lip covering 85 member is curled downward at the periphery, 6, to cover the lip of the bottle, and extends downward over the edge of the bottle, covering the same over the entire area which is ordinarily wet in pouring 90 liquid from the bottle, protecting the bottle lip at this point from dirt which would otherwise accumulate and be mixed with the liquid when poured. This outer or lip covering member, 5, is preferably of com- 95

paratively thin, tough paper, though the matter of relative thickness is not considered of primary importance. This member is cut near the center on an arc or U preferably concentric with the cap, the cut, 7, 100 being sufficient to form a suitable lifting tab. This tab is formed by cutting through the outer or lip covering member, 5, and the plug member, 4, the aperture being closed by the closing or reinforcing member, 8, it 105 being understood that the outside or lip covering member, 5, is secured to the plug member, 4, by a water proof paste, and that the closing or sealing member, 8, is likewise fastened to the inside of the plug member. 110

The cut, which forms the tab, severs both the outer member, 5, and the plug member, 4, so the tab is double as hereinafter described. In the form of the invention 5 shown, the ends of the arcuate cut in the plug member terminate in the body of the paper near the middle of the plug member, 4; these ends are so formed as to present what may be termed a double tearing 10 surface. This has two purposes, one is to avoid tearing of the tab, when it is used to remove the cap, the other is to afford evidence that the cap has been tampered with if an attempt is made to remove and replace it. The construction or expedient referred to consists in the formation of the stopper or plug member, 4, just beyond each end, 10, of the arcuate cut, 7, forming the tab, 9, a secondary cut, 11, transverse to the cut, 7, preferably curved around such point, 10, and comprising from 30 to 60 degrees less than a complete circle, the same being drawn around and concentric with the end of the cut.

25 It will be understood that there is formed in the plug, 4, a cut, 7, which registers with the cut, in the outer or lip covering member, 5; and that these two parts, 4 and 5, including the cut portion, are tightly glued 30 together, the completed tab, 13, being formed of the two overlying tabs, 12 and 9, also the inner closing or reinforcing member, 8, is pasted to the plug member, 4, on the inside of or beneath same so that the ends of the 35 cut, 7, with the non-tear encircling cuts, 11, are reinforced above and below. Thus we have a double tab formed with a non-tearing device at the base, the same being reinforced above and below.

40 When an excessive strain is applied to the tab in removing the cap in case the plug portion, 9, should tend to tear at the ends, 10, of the arcuate cut, and this cut is extended for a fraction of an inch, it merely 45 meets the arcuate cut, 11. Where the tendency to sever the material is distributed over an extended curved surface or edge, the actual tendency to part the fibers along the line on which they are already torn, being 50 thus eliminated and the rupture of the material completely arrested except at the ends of the extended curved surface or edge.

Having further reference to Figure 1, it 55 will be noted that this tab is raised or crimped near the base at 14, in a reverse curve which raises it to a plane above the cap and that it is supported in this position by a protuberance, 15, raised on the sealing 60 and reinforcing member, 8, directly beneath the tab, and in the aperture in the upper members, formed by cutting the tab.

Having further reference to the plug member, 4, it will be noted that this member 65 is in the form of a short hollow cylinder,

having an end, 16, secured to the outer or lip covering member 5, on one side and reinforced on the other side by the reinforcing and closing member, 8, the sides or cylindrical portion proper are indicated by 70 reference character, 17, forming a plug, which is inserted in the chambered portion, 2, of the bottle neck, and this plug portion is caused to fit tightly against the walls of the chambered portion, 2, as follows: The lower 75 edges of the cylinder proper, 17, are given an outward and upward reverse turn at 18, so that they are in effect doubled back on themselves, forming an upwardly turned flange, 19, and the extreme edge of the material is turned sharply outward at 20, preferably either at 90 degrees or a slightly greater angle, so that the edge of the paper at 21 is turned directly against the wall of the chambered portion of the neck at a sharp 85 angle, and pressed tightly against the wall as the cap is thrust into the bottle opening. The outer edge, 21, of the material forming the plug, being of slightly greater diameter than the chamber, 2, so that it is turned 90 slightly up as the cap is thrust in, and any attempt to withdraw the cap or any pressure resulting from the liquid within, causes something resembling a toggle action of this edge portion, increasing the pressure of the 95 edge against the chamber wall, as the pressure tending to withdraw the cap is increased.

When the cap is thus tightly seated, it will be apparent that it can only be withdrawn by inserting a sharp instrument under the edges, 6, by which the edges would be apparently damaged, or by inserting a sharp instrument in the cap, which would also cause an apparent injury, or by pulling 105 on the tab, 13, which would tear the edge of the cap as it is removed and cause distortion of the tab, so that in any event, if the cap is removed and replaced, the fact that it has been once removed will be apparent. 110

The cap is made from paper by means of suitable dies, cutting and pressing the parts, and then pasting and assembling them.

I have thus described, specifically and in detail, a single embodiment of my invention 115 in order that its nature and operation may be clearly understood. However, the specific terms herein are used descriptively rather than in a limiting sense, the scope of the invention being defined in the claims.

What I claim and desire to secure by Letters Patent is:

1. A bottle cap of sheet material, having a U shaped cut, forming a lifting tab with transverse cuts at the end of the U to distribute the stress and prevent tearing. 125

2. A bottle cap of sheet material having a U shaped cut forming a lifting tab with cuts curved about the ends of the cut to prevent tearing.

3. A bottle cap consisting of an outer lip covering member of sheet material, a hollow plug also of sheet material, the two being pasted together in close contact, both members having a U shaped cut forming a lifting tab, the plug member having a cut adjacent the ends of the U shaped cut to distribute the stress applied to the tab and prevent tearing.
- 10 4. A bottle cap of sheet material, consisting of an outer lip covering member, a plug member, the two being secured together in close contact, a U shaped cut in both members forming a lifting tab, the plug member having a transverse cut adjacent each end of the U shaped cut to distribute and prevent or limit tearing, and an inner closing member secured to the inside of the plug.
- 5 5. A bottle cap of sheet material, consisting of an outer lip covering member, a plug member of sheet material, having its edges turned downward and then doubled outward and upward, doubling the bottom edge of the plug, the extreme edge being turned outward substantially at right angles so the edge of the material contacts with the inner surface of the bottle neck.
- 15 6. A bottle cap of sheet material, consisting of an outer lip covering member, a plug member of sheet material, having its edges turned downward and then doubled outward and upward, doubling the bottom edge of the plug, the extreme edge being turned outward substantially at right angles so the edge of the material contacts with the inner surface of the bottle neck, so that it is turned slightly upward from a right-angled position as it is inserted, giving it a toggle action with increased pressure on the walls of the bottle neck as it is withdrawn.

Signed by me at Baltimore, Maryland,
this 21st day of January, 1920.

CHARLES C. PARKER.
